(74) *Attorney, Agent, or Firm* — McDermott Will & Emery LLP

(57) **CLAIM**

We claim the ornamental design for a folding tricycle, as shown and described.

DESCRIPTION

FIG. 1 is a front and top perspective view of a folding tricycle in accordance to our new design.

FIG. 2 is a back and bottom perspective view of the folding tricycle shown in FIG. 1.

FIG. 3 is a right side view of the folding tricycle shown in FIG. 1.

FIG. 4 is a left side view of the folding tricycle shown in FIG. 1.

FIG. 5 is a front view of the folding tricycle shown in FIG. 1.

FIG. 6 is a back view of the folding tricycle shown in FIG. 1.

FIG. 7 is a top view of the folding tricycle shown in FIG. 1; and,

FIG. 8 is a bottom view of the folding tricycle shown in FIG. 1.

The broken lines in the drawings illustrate features of the folding tricycle that forms no part of the claimed design.

1 Claim, 7 Drawing Sheets
